No. 772,673.

PATENTED OCT. 18, 1904.

A. C. ROEBUCK & F. McMILLAN.

CARBURETER.

APPLICATION FILED DEC. 7, 1903.

NO MODEL.

UNITED STATES PATENT OFFICE.

ALVAH C. ROEBUCK AND FRANK McMILLAN, OF CHICAGO, ILLINOIS.

CARBURETER.

SPECIFICATION forming part of Letters Patent No. 772,673, dated October 18, 1904.

Application filed December 7, 1903. Serial No. 184,035. (No model.)

To all whom it may concern:

Be it known that we, ALVAH C. ROEBUCK and FRANK McMILLAN, citizens of the United States, residing at Chicago, in the county of 5 Cook and State of Illinois, have invented certain new and useful Improvements in Carbureters for Calcium-Light Apparatus; and we do hereby declare the following to be a full, clear, and exact description of the same, reference being had to the accompanying drawings, forming a part of this specification.

The present invention relates to portable calcium-light apparatus, and more particularly to that type of such apparatus in which 15 oxygen is generated as required and by passage through a carbureter is saturated with a volatile hydrocarbon previous to its passage to the calcium-burner of a stereopticon or the like; and the present improvement has for 20 its object to provide a simple and efficient structural arrangement and combination of parts in a carbureter by means of which the saturation of the passing gas is effected in a very thorough manner and by means of which 25 the degree of saturation is automatically maintained at a uniform standard regardless of the usual variations of the atmospheric temperature due to change of seasons and the like, all as will hereinafter more fully appear and be 30 more particularly pointed out in the claims.

In the accompanying drawings, illustrative of the present invention, Figure 1 is a side elevation with parts in section, illustrating the present invention in its application to the 35 calcium-light of a stereopticon. Fig. 2 is a vertical sectional elevation of a carbureter embodying the present invention and taken on line $\alpha\alpha$, Fig. 3. Fig. 3 is a horizontal sectional elevation on line $\alpha'\alpha'$, Fig. 2.

Similar numerals of reference indicate like 40 parts in the different views.

Referring to the drawings, 1 represents the usual closed gas-generating chamber, near the bottom of which is arranged the holder 2 for 45 the solid chemical, usually sodium binoxid, from which the oxygen gas is generated in an automatic manner by the contact of water with said chemical, such water being supplied from an overhead tank 3 and introduced into 50 the bottom part of the chamber 1 by a supply-

pipe 4, reaching to near the bottom of said chamber, as usual, and common to the present form of gas-generating apparatus.

5 is a valved outlet-neck arranged at the upper end of the casing 1 and having a tubular 55 connection 6, preferably in the form of a flexible hose, with the carbureter, as hereinafter described, in order to conduct the oxygen gas which collects under pressure in the upper part of the aforesaid casing 1 to said carbureter 60 previous to the delivery of such gas to the burner of the stereopticon-lamp 7 or other like apparatus.

8 is the vertical cylindrical casing of the carbureter, provided with closure-heads 9 at 65 its respective ends and one or both of which are removable for access to the carbureter parts contained within the aforesaid casing 1.

10 is a casing arranged outside the carbureter-casing 8 and concentric therewith to 70 form an annular chamber 11 and which chamber incloses more or less of the vertical height of the carbureter and in functions in the present invention acts as a separator for the water of entrainment carried over by the gas 75 from the generator-chamber 1 and as a means for imparting heat from the incoming gas to the inclosing casing and contents of the carbureter to compensate for the loss of temperature in same due to the vaporization of the 80 ether or other equivalent volatile substance within the carbureter during the continued operation of the present apparatus. By this means the heat generated by the chemical action in the generator 1 is utilized in a simple 85 and automatic manner in compensating for the cooling action in the carbureter due to the evaporation of its volatile filling and with the result that the temperature of the carbureter is maintained at a uniform stage best 90 adapted for a perfect operation of the apparatus.

12 is the inlet neck or passage of the annular chamber 11, to which the tubular connection 6, before mentioned, is attached. 95

13 is the outlet neck or passage of the annular chamber 11, to which is attached the tubular connection 14, which extends to the inlet-neck of the carbureter.

15 is an annular shell closed at its lower end 100

by a closure-head and secured at its upper end to the upper head of the carbureter. Such shell divides the interior of the carbureter-casing 8 into an outer annular subchamber 5 and an inner cylindrical subchamber, as illustrated in Fig. 2 of the drawings.

16 is an annular roll of woven fabric constituting a porous filling for the annular subchamber aforesaid and which in actual use is 10 saturated with ether or like volatile hydrocarbon usually employed in the present type of apparatus.

17 is a loose filling of cotton or other like fibers within the cylindrical subchamber 15 aforesaid and which is adapted to assist in preventing a retrograde flow through the carbureter.

18 is an inverted-U-shape tube arranged vertically within the shell 15 aforesaid, with one 20 end or leg extending through the bottom closure-head of such shell and with the other end arranged a small distance above such closure-head, as shown in Fig. 2.

19 is the inlet neck or passage of the carbureter communicating with the top of the cylindrical subchamber aforesaid and provided with a controlling-valve 20. Such neck or passage is also provided with a nipple on its outer or free end for the convenient attachment 30 of the end of the tubular connection 14, before described, and which forms the conducting connection between the outlet-neck 13 aforesaid and the inlet-neck of the carbureter.

35 21 is the outlet neck or passage of the carbureter provided with a nipple at its outer end for the convenient attachment of the usual flexible section of tubing 22, which extends to the burner of the stereopticon 7 and is 40 adapted to carry a supply of saturated oxygen to such burner.

23 is a branch neck or passage connecting with the inlet-neck 19 aforesaid of the carbureter and provided with a controlling-valve 45 24.

Such branch neck or passage is provided at its outer end with an attaching-nipple for the section of flexible tubing 25, which also extends to the burner of the stereopticon 7 and is adapted to conduct a supply of oxygen 50 gas to such burner.

36 is a closure-plug fitting an overflow-orifice in the casing 8 of the carbureter a short distance from the upper end of the same and is adapted in the operation of filling the carbureter with ether through one of the openings of the same to indicate by an overflow at such orifice that the proper amount of ether has been introduced into the carbureter.

The operation of the present apparatus is 60 as follows: With the descent of the water from the elevated tank 3 into the lower part of the generator-chamber 1 and with the contact of such water with the binoxid of soda therein the oxygen gas is generated and accumulates under pressure in said chamber

and with the attainment of a predetermined pressure prevents a further generation of gas by a return displacement of the water toward the elevated tank 3 in manner usual to the present type of gravity-controlled gas-generators. The oxygen gas passes into the annular chamber 11, where the water of entrainment is separated and the heat of the gas imparted to the carbureter in manner heretofore described, after which it passes to the inlet-neck 19, at which point the course of the gas divides, one portion, controlled by the valve 24, passing in a direct manner to the burner of the stereopticon 7 through the flexible connection 25, while the other portion, controlled by the valve 20, passes down the inner cylindrical subchamber of the carbureter and from thence through the U-shaped tube 18 into the bottom part of the carbureter and up through the annular filling contained in the annular subchamber of the carbureter to the outlet-passage 21, from whence the gas passes in a properly-saturated condition to the burner of the stereopticon through the flexible connection 14.

Having thus fully described our invention, what we claim as new, and desire to secure by Letters Patent, is—

1. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an inlet-neck connected to 95 the inner subchamber, and an outlet-neck connected to the annular subchamber, substantially as set forth.

2. In a carbureter of the type herein described, the combination of a carbureter-casing, closure-heads for the ends of the same, an inner shell dividing the carbureter-casing into an inner subchamber and an outer annular subchamber, a porous filling formed by an annular roll of fabric in said annular subchamber, an inlet-neck connected to the inner subchamber, and an outlet-neck connected to the annular subchamber, substantially as set forth.

3. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an inlet-neck connected to the inner subchamber, an outlet-neck connected to the annular subchamber, and an outer chamber surrounding the carbureter-casing and adapted to form a separating-chamber for the entrainment-water of the gas and a heater for the carbureter, substantially as set forth.

4. In a carbureter of the type herein described, the combination of a carbureter-casing, closure-heads for the ends of the same, an inner shell dividing the carbureter-casing

into an inner subchamber and an outer annular subchamber, a porous filling formed by an annular roll of fabric in said annular subchamber, an inlet-neck connected to the inner subchamber, an outlet-neck connected to the annular subchamber, and an outer chamber surrounding the carbureter-casing and adapted to form a separating-chamber for the entrainment-water of the gas and a heater for the carbureter, substantially as set forth.

5. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an inlet-neck connected to the inner subchamber, an outlet-neck connected to the annular subchamber, and an inverted-U-shaped tube arranged within the inner subchamber and opening at one end into the bottom portion of such chamber and at the other end into the annular subchamber, substantially as set forth.

25 6. In a carbureter of the type herein described, the combination of a carbureter-casing, closure-heads for the ends of the same, an inner shell dividing the carbureter-casing into an inner subchamber and an outer annular subchamber, a porous filling formed by an annular roll of fabric in said annular subchamber, an inlet-neck connected to the inner subchamber, an outlet-neck connected to the annular subchamber, and an inverted-U-shaped 30 tube arranged within the inner subchamber and opening at one end into the bottom portion of such chamber and at the other end into the annular subchamber, substantially as set forth.

40 7. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an inlet-neck connected to the inner subchamber, an outlet-neck connected to the annular subchamber, an inverted-U-shaped tube arranged within the inner subchamber and opening at one end into the bottom portion of such chamber and at the other end into the annular subchamber, and an outer chamber surrounding the carbureter-casing and adapted to form a separating-chamber for the entrainment-water of the gas and a heater for the carbureter, substantially as set forth.

55 8. In a carbureter of the type herein described, the combination of a carbureter-casing, closure-heads for the ends of the same, an inner shell dividing the carbureter-casing

into an inner subchamber and an outer annular subchamber, a porous filling formed by an annular roll of fabric in said annular subchamber, an inlet-neck connected to the inner subchamber, an outlet-neck connected to the annular subchamber, an inverted-U-shaped tube arranged within the inner subchamber and opening at one end into the bottom portion of such chamber and at the other end into the annular subchamber, and an outer chamber surrounding the carbureter-casing and adapted to form a separating-chamber for the entrainment-water of the gas and a heater for the carbureter, substantially as set forth.

65 9. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an outlet-neck connected to the inner subchamber, a valve controlling said inlet-neck, an independent branch neck on said inlet-neck, a valve controlling said branch neck, and an outlet-neck connected to the annular subchamber, substantially as set forth.

70 10. In a carbureter of the type herein described, the combination of a carbureter-casing, closure-heads for the ends of the same, an inner shell dividing the carbureter-casing into an inner subchamber and an outer annular subchamber, a porous filling formed by an annular roll of fabric in said annular subchamber, an inlet-neck connected to the inner subchamber, a valve controlling said inlet-neck, an independent branch neck on said inlet-neck, a valve controlling said branch, and an outlet-neck connected to the annular subchamber, substantially as set forth.

75 11. In a carbureter of the type herein described, the combination of a carbureter-casing, closure-heads for the ends of the same, an inner shell dividing the carbureter-casing into an inner subchamber and an outer annular subchamber, a porous filling in said annular subchamber, an inlet-neck connected to the inner subchamber, a valve controlling said inlet-neck, an independent branch neck, an outlet-neck connected to the annular subchamber, and an outer chamber surrounding the carbureter-casing and adapted to form a separating-chamber for the entrainment-water of the gas, and a heater for the carbureter, substantially as set forth.
